Adam Reid
INVENTOR.

UNITED STATES PATENT OFFICE.

ADAM REID, OF BUFFALO, NEW YORK.

DESIGN FOR A CAKE-PAN.

Specification forming part of Design No. 5,132, dated July 18, 1871.

To all whom it may concern:

Be it known that I, ADAM REID, of the city of Buffalo, county of Erie, State of New York, have invented and produced a new and original Design for Cast-Iron Cake-Pan, of which the following is a specification:

The nature of my design for cake-pan consists in combining a variety of patterns and shapes to a cake-pan, as represented in the accompanying drawing.

In the ends of pan are openings A A, into which the ordinary stove-cover handle fits, so that it can be moved the same as a spider on the top of the stove.

There can be no doubt but that the combining of a variety of patterns into one baking-pan makes it more convenient and much more desirable.

Having thus fully described the nature of my design, what I desire to secure by Letters Patent as my invention is—

The design for a cake-pan, as shown and specified.

ADAM REID.
